John F. Rathbone, Albany, N.Y.
Letters Patent No 396, dated July 8th 1851

The Schedule referred to in these Letters Patent and making part of the same
To whom it may concern

Be it known that I, John F. Rathbone of the City of Albany and State of New York have produced a new and original ornamental design for the plates of a casting stove; and I hereby declare that the annexed drawings are full and accurate delineations of the said plates with their ornamental parts which are combined to form the stove, with the exception of the bottom plate, the side plate not represented being symmetrically similar to the one shown and the half of the front plates and hearth plate not represented being also symmetrically similar to the half shown.

What I claim as my production, and desire to secure by Letters Patent is the combination and arrangement of

2

Ms. 396

ornamental figures and forms represented in the accompanying drawings forming together the ornamental designs for the plates of a work
in
stone
